(57) **CLAIM**

The ornamental design for an accelerator pedal for motor vehicle as shown and described.

DESCRIPTION

FIG. 1 is a perspective view of an accelerator pedal for motor vehicle showing my new design;

FIG. 2 is a front view thereof;

FIG. 3 is a right view thereof;

FIG. 4 is a left view thereof; and,

FIG. 5 is a top view thereof.

The broken lines in the drawings illustrate portions of the accelerator pedal for motor vehicle that form no part of the claimed design.

1 Claim, 5 Drawing Sheets
